ABSTRACT OF THE DISCLOSURE

A calculator for arithmetical calculations is disclosed comprising a case containing a plurality of round dowels side by side with their axes disposed in a common plane, the dowels are moveable in respect to the case, the case bearing indicia used in conjunction with the movement of said dowels for said arithmetical calculations, the dowels commonly visible in respect to the indicia on the case, each dowel both axially slidable and rotatable in respect to said case.

The present invention while relating broadly to calculating devices in general, has more particular reference to a relatively small and compact manually operable instrument that can be carried in a pocket or purse and thus be readily accessible for use at all times, the main objective of the invention being the provision of a calculator of the character described particularly adapted for use by engineers, draftsmen and others, whereby answers to arithmetical calculations in addition, subtraction, multiplication and division may be quickly and easily obtained and visually indicated.

Another object of the invention is to provide a simple calculating device which will not only be attractive and interesting to children but a valuable aid in learning addition, subtraction and, particularly, the multiplication tables.

A further and important object of the invention is the provision of a calculating device of but few parts which is of durable and practical construction, inexpensive to manufacture and not liable to derangement.

Other objects and advantages of the invention will become apparent from a consideration of the following detailed description taken in connection with the accompanying drawing wherein a satisfactory embodiment of the invention is shown. However, it is to be understood that the invention is not limited to the details disclosed but includes all such variations and modifications as fall within the spirit of the invention as defined herein.

In the drawing:

FIGURE 1 is a top plan view of an easy calculator embodying the invention;

FIGURE 2 is a right side view of said embodiment;

FIGURE 3 is a fragmentary view of said embodiment with parts in section; said view being generally as taken on the line 3—3 of FIG. 2;

FIGURE 4 is a top plan view of said embodiment shown broken into top and bottom portions; the dowels in the top portion being arranged for addition or subtraction and in the bottom portion for multiplication or division.

The easy calculator comprises, in the instance shown, nine dowels 5 preferably of equal length and arranged side by side in a row in the pocket 6 formed within a rectangular case generally indicated at 7. The pocket 6 is rectangular in transverse cross-section and the axes of the dowels 5 lie in a common plane therein. The line 13 indicates one of the long sides of the pocket 6. The body portion of the case 7 comprises a bottom wall 8, side walls 9 and an end wall 10; the free edges of the side walls 9 may be bent outwardly to form flanges 11. Bond-

2

ed or otherwise secured to the flanges 11 is a cover plate 12 of transparent plastic. The term "dowel" as used herein includes in its meaning any cylindrical rod.

When not in use all of the dowels 5 have their contained ends bottoming against or abutting the end wall 10 of the case 7. The free ends of the dowels 5 extend beyond the open end of the case 7 to provide finger engaging portions for manipulation of the dowels by the hand of the person using the easy calculator. The dowels 5 are capable of both axial sliding and rotational movement within the pocket 6.

The surface of cover plate 12 is preferably provided with axially spaced transverse hairlines 14. A horizontal row of numbers from 0 to 9 is visible along the upper edge of the cover plate 12 above the dowels 5 which are used in addition and subtraction. Another horizontal row of numbers from 1 to 9 is visible along the lower edge of the cover plate 12 below the dowels 5 which are used in multiplication and division.

Each of the dowels 5 bear nine numbers on its top surface which are visible through the cover plate 12. The first number on the uppermost or first dowel (as viewed in FIG. 1) is 1 and the nine numbers thereon are separated in numerical quantity by 1; the first number on the second dowel is 2 and the nine numbers thereon are separated in numerical quantity by 2; this arrangement is repeated down to the lowermost or ninth dowel, the first number of which is 9 and the nine numbers thereon are separated in numerical quantity by 9. The dowels 5, taken collectively, thus have the multiplication tables 1 through 9 printed thereon as shown. Each dowel 5 has axially spaced transverse notches 15 (see FIGURE 3) adapted to receive in holding engagement a V-shaped tooth 16 on a spring arm 17 secured by a rivet 18, or other means, to the bottom 8 of casing 7. This arrangement yieldably holds the dowels wherever they are positioned in said pocket against axial sliding movement.

To facilitate reading of the results in multiplication every other transverse row of numbers on the dowels is preferably provided with a colored background such as a red background.

The following paragraph is an explanation of use of the easy calculator in addition:

In addition and subtraction the dowels are turned down, that is, rotated so that the numbers thereon are not visible through the cover plate 12. The uppermost or first dowel represents the UNITS place; the second dowel the TENS place; the third dowel the HUNDREDS place, etc. The dowels are axially slid from left to right (as viewed in the upper portion of FIG. 4) in addition and from right to left in subtraction. The upper portion of FIG. 4 illustrates the quantity 71 by the positions of the second and first dowels, respectively, the contained ends of which are indicated in dotted lines and shown disposed beneath the top row numerals 7 and 1, respectively. 21 is added to the quantity 71 by axially sliding the second dowel to the right two TENS to beneath the top row number 9 and by axially sliding the first dowel to the right one UNIT to beneath the top row number 2. The sum quantity 92 is illustrated in the upper portion of FIG. 4 by the contained ends of the second and first dowels which are shown and indicated in full lines.

The following paragraph is an explanation of the use of the easy calculator in multiplication and division:

The lower portion of FIG. 4 shows the four lowermost dowels set up with the number 9876 ready for multiplication by the multipliers 2 through 9 in the bottom row. The leftmost number (in this case 9) is set up on the lowermost dowel to the extreme left of the pocket and the next number (in this case 8) is set up on the second lowermost dowel displaced one digit to the right and so on

to the units number (in this case 6). The product 19752 of the multiplier 2 can be seen in FIG. 4; (this product 19752 can be seen in FIG. 4 if the viewer mentally adds the staggered numbers 18, 16, 14 and 12 above the multiplier 2) likewise the product 29628 of the multiplier 3; likewise the product 39504 of the multiplier 4; and so on to the product 88884 of the multiplier 9.

In multiplication the multiplicand and in division the divisor is thus set up on the dowels in staggered fashion to the right as shown in FIG. 4 for the number 9876.

For an example of the use of the calculator in multiplication, assume that 987.6 must be multiplied by 8.79. The product of 9876 as the multiplicand with the multiplier 9 is read off the calculator as shown in FIG. 4 to be 88884 and written on paper under the line beneath 8.79 with the 4 of 88884 beneath the 9 of 8.79. The product of 9876 with the multiplier 7 is next read off the calculator as shown in FIG. 4 to be 69132 and written on paper beneath 88884 but shifted one digit to the left in the usual manner. The product of 9876 with the multiplier 8 is then read off the calculator as shown in FIG. 4 to be 79008 and written on paper beneath 69132 but shifted one digit to the left in the usual manner. The three separate products are then added in the usual manner on paper to obtain the final product 8681.004.

The calculator is used in division to assist in finding the correct quotient more quickly. For example, assume that 241,962 must be divided by 9876. The divisor 9876 is set up on the dowels as shown in the lower portion of FIG. 4. The first step is to find the correct first digit of the quotient which is seen to be 2 since the product of the multiplier 2 with the divisor 9876 is seen in FIG. 4 to be 19752 which is the closest product less than 24196. (The product of the multiplier 3 with the divisor 9876 is seen in FIG. 4 to be 29628 and hence too large for 3 to be the first digit of the quotient.) The first subtraction step in the division is carried out on paper resulting in 44442 (2 carried from the dividend) and the second digit of the quotient is sought and found to be 4 since the product of the multiplier 4 with the divisor 9876 is seen in FIG. 4 to be 39504 which is the closest product less than 44442. (The multiplier 5 yielding a product of 49380 is seen to be too large.) The second subtraction step in the division is carried out on paper resulting in 49380 (0 carried from the dividend after placing the decimal point after 241,962) and the third digit of the quotient is sought and found to be 5 since the product of the multiplier 5 with the divisor 9876 is seen in FIG. 4 to be 49380. Consequently the correct quotient is 24.5.

In conclusion it may again be stated that cover 12 has hair lines and numbers, as shown in plan view, and that the dowels 5 (1 thru 9) have multiplication tables printed thereon, also as shown, that they are notched diametrically opposite the number so as to make positioning of the dowels fast in adjusted positions thereof in the manner set forth.

In addition and subtraction the dowels representing UNITS, TENS, HUNDREDS, etc. as required, are turned down so that the numbering thereon does not show. In addition the dowels are moved from left to right. In addition when a dowel is moved to the extreme left (i.e. the contained end of the dowel is moved beneath zero in the top row of numbers) the dowel beneath (as viewed in FIGS. 1 and 4) must be moved one number to the right.

For example:

$$546 + 186 = 732.$$

6+6=12. Move #1 dowel from beneath the number 6 to the extreme right to beneath the number 9 and then to the extreme left to beneath the number zero and then to the right to beneath the number 2.

4+8+1=13. Move #2 dowel from beneath the number 4 to the extreme right to beneath the number 9 and then to the extreme left to beneath the number zero and then to the right to beneath the number 3.

5+1+1=7. Move #3 dowel from beneath the number 5 to the right to beneath the number 7.

To subtract the dowels are moved from right to left. In subtraction when a dowel is moved to the extreme right (i.e. the contained end of the dowel is moved beneath the number 9 in the top row of numbers) the dowel beneath (as viewed in FIGS. 1 and 4) must be moved one number to the left.

For example:

$$732 - 546 = 186.$$

12-6=6. Move #1 dowel from beneath the number 2 to the extreme left to beneath the number zero and then to the extreme right to beneath the number 9 and then to the left to beneath the number 6.

13-1-4=8. Move #2 dowel from beneath the number 3 to the extreme left to beneath the number zero and then to the extreme right to beneath the number 9 and then to the left to beneath the number 8.

7-1-5=1. Move #3 dowel to the left from beneath the number 7 to beneath the number 1.

To multiply, the first figure of any number must be at the extreme left end of the case 7.

What I claim is:

1. A calculator for arithmetical calculations comprising a case containing a plurality of round dowels side by side with their axes disposed in a common plane, said dowels moveable in respect to said case, said case bearing indicia used in conjunction with the movement of said dowels for said arithmetical calculations, said dowels commonly visible in respect to said indicia on the case, each dowel both axially slideable and rotatable in respect to said case, said dowels bearing indicia on the top surfaces thereof used in multiplication and division and being blank on the bottom surfaces thereof for use in addition and subtraction, said indicia on the case including along one side of the plurality of dowels a row of consecutive numbers used in addition and subtraction when the dowels used in addition have been rotated to show their blank bottom surfaces, said indicia on the case further including along the opposite side of the plurality of dowels another row of consecutive numbers used in multiplication and division when the dowels used in multiplication and division have been rotated to show their indicia bearing top surfaces, said last-mentioned dowels bearing via said indicia on their top surfaces the multiplicand in multiplication and the divisor in division.

2. A calculator as claimed in claim 1, and means for yieldably holding the dowels wherever they are positioned in respect to said case in carrying out said arithmetical calculations.

3. A calculator as claimed in claim 1, said dowels being nine in number, said indicia on the top surfaces thereof collectively comprising the multiplication tables from 1 through 9.

4. A calculator as claimed in claim 1, said case having a pocket therein with a blind end and an open end and top and bottom walls, said dowels contained in said pocket and having free ends projecting out of said open end, said dowels individually insertable into and removable from said pocket and being moveable therein, the contained ends of said dowels capable of bottoming against said blind end, said case having a cover plate, the cover plate for the case being the top wall of the pocket and being transparent so that the dowels are visible therethrough.
